UNITED STATES PATENT OFFICE.

JOSEPH WARREN CUTLER, OF ROCHESTER, NEW YORK, ASSIGNOR TO CUTLER MANUFACTURING COMPANY, OF ROCHESTER, NEW YORK, A CORPORATION OF NEW YORK.

LOCKING DEVICE FOR MAIL-CHUTES.

No. 881,112.

Specification of Letters Patent.

Patented March 10, 1908.

Application filed January 6, 1906, Serial No. 294,824. Renewed November 4, 1907. Serial No. 400,549.

To all whom it may concern:

Be it known that I, JOSEPH WARREN CUTLER, of Rochester, in the county of Monroe and State of New York, have invented certain new and useful Improvements in Locking Devices for Mail-Chutes; and I do hereby declare the following to be a full, clear, and exact description of the same, reference being had to the accompanying drawing, forming a part of this specification, and to the reference-numerals marked thereon.

My present invention relates to improvements in mail chutes such as are usually constructed to extend through the floors of a building to a collection receptacle for facilitating the collection of postal matter from a building, and the object of the present invention is to provide an improved locking device adapted to be applied to a base section, or other part of the chute, whereby such part or parts may be locked in place under normal conditions, but which, when necessary, may be quickly unlocked and removed to render the interior or other portions of the chute accessible.

To these and other ends the invention consists in certain improvements and combinations of parts all as will be hereinafter more fully explained, the novel features being pointed out in the claims at the end of the specification.

In the drawing:—Figure 1 represents a vertical section through a portion of a chute and a base section, constructed in accordance with my invention, and Figs. 2 and 3 are perspective views of the upper and lower members respectively of the base section for the chute.

Similar parts in the several views are designated by the same reference numerals.

Mail chutes as usually constructed extend vertically through the several floors of buildings to a collection receptacle usually located on the lower or ground floor, and the present embodiment of my invention is shown applied to a base section adapted to fit around the chute at the floor not only for the purpose of protecting it from being crushed or damaged, but also to cover and conceal the floor section and the adjacent parts of the chute.

In the present embodiment of my invention 1 designates a section of the chute above the floor 2, a bracket 3 being secured to a suitable backing 4 and provided with suitable

means for fastening the attaching flange 5 of chute section 1. The bracket 3 also serves to secure the attaching flange 6 of the floor section 7 of the chute, the latter extending through a vertical passage 8 formed in the floor.

The base section embodies a lower member 9 in the form substantially of a rectangular frame which preferably rests on the floor and surrounds the chute, the rear part 10 of the frame being secured by the securing devices 11 to the backing 4, the front of the frame having an upward extension 12 having an apertured staple 13 projecting forwardly therefrom. The upper member 14 of the base section is adapted to be supported by the lower member and conforms generally to the outline of the frame, and it comprises a frame having a front and two sides, the rear thereof being open to enable it to be fitted against the chute while the latter is in position, the lower front edge of the upper member being provided with one or more projections 15 arranged to engage at the rear of the corresponding part of lower member 9. An aperture 16 is formed at the proper point in the front of the upper member to receive the forwardly-projecting staple 13 on the lower member, and as the projections 15 of the upper member are engaged with the lower member and the upper member is then tilted rearwardly against the vertical extension 12, the staple 13 will pass through the aperture 16 of the upper member and project through to the front surface thereof, and by passing a bolt or bow of a lock 17 through the aperture of the staple, the upper member will be firmly locked to the lower member.

As the lower base member 9 is fixed in position by securing devices 11 which are preferably located within the base, it will be impossible for unauthorized persons to remove it, as it will be necessary to unlock and remove the upper member in order to do this, and as the floor section of the chute, and also the securing devices for the floor and adjacent sections of the chute are inclosed and concealed by the base section when its parts are in locked position, and as the lock is controlled by a key in possession of the proper authorities, this portion of the chute will be effectually protected from tampering or interference therewith in any way by unauthorized persons. However, it will be understood that the chute locking

means embodying my present invention is not only adapted to the base sections, but is also applicable to other parts of the chute, such for instance as the securing or supporting devices for holding or locking the chute sections in position to prevent their removal or opening, and the present invention provides effective means for locking the chute and thus prevents unauthorized access thereto, as the staple or part adapted to receive the lock is secured by screws or equivalent securing devices which are concealed or inaccessible when the parts are in locked position, and hence all of the parts are under control of the lock.

I claim as my invention:

1. The combination with a mail chute, of a base section therefor embodying a removable member, and a locking device for the 20 said member.

2. The combination with a mail chute, of a base section for protecting a portion of the chute, embodying a relatively fixed member, a movable member, and a locking device 25 for controlling relative movement of the movable and fixed members.

3. The combination with a mail chute adapted to extend through the floors of a building, of a base section for protecting the 30 chute adjacent to the floor embodying a relatively fixed member, a relatively movable member adapted to coöperate with the fixed member and a lock for preventing unauthorized movement of the movable member.

4. The combination with a mail chute embodying one or more sections, and securing means therefor, of a base section adapted to conceal the chute-securing means, and a 40 lock for preventing unauthorized movement or removal of the base section.

5. The combination with a mail chute embodying a floor section; and securing means for said section, of a base section 45 adapted to conceal said securing means, and a lock for preventing unauthorized removal of the base section.

6. The combination with a mail chute, of a base section therefor embodying a frame 50 surrounding the chute, a backing, means operable from the inner side of the frame for securing it to the backing, a movable member embracing the chute and coöoperating with said frame, and a lock for preventing unauthorized removal of said movable member.

7. The combination with a backing and a mail chute secured thereto, of a base section 60 for the chute embodying a frame embracing the chute and secured to the backing, a detachable member having retaining projections thereon arranged to coöperate with the frame, and a locking device for preventing unauthorized removal of the detachable 65 member.

8. The combination with a suitable backing, and a mail chute secured thereto, of a base section for the chute embodying a frame secured to the backing and having a staple thereon, a detachable member formed to fit the frame and arranged to embrace the chute, said member having an aperture to receive the staple, and a locking device co-operating with the staple to prevent unauthorized removal of the detachable member. 70

9. The combination with a suitable backing, and a mail chute secured thereto and extending through a floor of a building, of a base section for the chute embodying a frame secured to the backing and surrounding the 80 chute adjacent to the floor, an extension on the frame carrying a forwardly-projecting staple, a detachable member having projections thereon arranged to detachably engage at the inner side of the frame, said member being formed to embrace and protect the chute and having an aperture to receive the staple on the frame, and a lock coöperating with the staple to prevent unauthorized removal of the detachable member. 85

10. The combination with a suitable backing, and a mail chute adapted to be secured thereto, of locking means for the chute embodying a lock-receiving device, concealable securing means for the said device, and a 95 chute-engaging member controlled by a lock and serving to conceal the said securing means.

11. The combination with a suitable backing, and a mail chute adapted to be secured 100 thereto, of locking means for the chute embodying a lock-receiving device, means for securing said device to the backing, a member serving to conceal the said securing means, and a lock coöperating with the lock-receiving device and said member for preventing unauthorized movement of the latter. 105

12. The combination with a suitable backing, and a mail chute adapted to be secured 110 thereto, of locking means for the chute embodying a lock-receiving staple, concealable securing devices for fastening the staple to said backing, a chute-securing member adapted to coöperate with the chute, and a lock 115 having a part to coöperate with the staple and secure the chute-securing member in locked position.

13. The combination with a suitable backing, and a mail chute adapted to be secured 120 thereto and having a part to be locked in co-operative relation therewith, of a lock-receiving device, means arranged to be concealed by said part when in locked position for securing said device to the backing, and a lock 125 coöperating with said lock-receiving device and part for preventing unauthorized movement of the latter.

14. The combination with a suitable backing, and a mail chute adapted to be secured 130

thereto, of locking means for the chute embodying a staple, means for securing the staple to the backing, a member serving to conceal the said securing means, and a lock for preventing unauthorized movement of said member.

15. The combination with a suitable backing, and a mail chute adapted to be secured thereto, of a relatively fixed member having a part thereon adapted to coöperate with a lock, means for securing said member to the backing, a movable member serving to conceal the securing means for the fixed member, and a lock adapted to coöperate with the corresponding part of the fixed member to prevent unauthorized movement of the movable member.

16. In a mail chute, the combination with a bracket adapted to be fastened to a wall and having a lock engaging member thereon, of a chute adapted to be secured by the bracket, a detachable member coöoperating with the chute, and a lock having a part co-operating with the lock engaging member on the bracket for preventing unauthorized removal of said detachable member.

17. Means for locking a mail chute from unauthorized removal embodying a support having a lock receiving device, a detachable

member adapted to coöperate with a portion 30 of the chute and a lock adapted to be applied to the lock receiving device of the support to secure the said member from removal.

18. The combination with a mail chute, of a support having a staple secured thereto, a member adapted to secure a part of the chute in position and a lock coöperating with said staple and member to prevent unauthorized removal of the latter.

19. The combination with a mail chute, of a support having a staple, a member adapted to secure a part of the chute having detachable connections with the support and adapted to accommodate the staple and a lock coöperating with the staple for preventing unauthorized removal of said member.

20. The combination with a mail chute, of a support having a staple thereon, a member detachably secured at one point to said support, and formed to accommodate said staple, 50 said member being adapted to retain a part of the chute in position and a lock coöperating with said staple for preventing unauthorized removal of said member.

JOSEPH WARREN CUTLER.
